US0D1093389S

(12) **United States Design Patent** (10) Patent No.: **US D1,093,389 S**
(45) Date of Patent: ** Sep. 16, 2025

(54) **DOCKING STATION**

(71) Applicant: **Dell Products L.P.**, Round Rock, TX (US)

(72) Inventors: **Paul J. Doczy**, Austin, TX (US); **Marcel Souza**, Pflugerville, TX (US); **Sarah Eleanor Michener Wartofsky**, Cedar Park, TX (US)

(73) Assignee: **Dell Products L.P.**, Round Rock, TX (US)

(**) Term: **15 Years**

(21) Appl. No.: **29/942,588**

(22) Filed: **May 16, 2024**

(51) LOC (15) Cl. **14-02**

(52) U.S. Cl.

USPC **D14/434**

(58) **Field of Classification Search**

(57) **CLAIM**

The ornamental design for a docking station as shown and described.

DESCRIPTION

FIG. 1 is a front perspective view of the docking station comprising the present invention;

FIG. 2 is a front elevation view thereof;

FIG. 3 is a rear elevation view thereof;

FIG. 4 is a right side view thereof;

FIG. 5 is a left side view thereof;

FIG. 6 is a top view thereof;

FIG. 7 is a bottom view thereof;

FIG. 8 is a bottom rear perspective view thereof;

FIG. 9 is a bottom rear perspective view thereof; and,

FIG. 10 is a bottom rear perspective view thereof.

Broken lines shown in the drawings illustrate portions of the docking station that form no part of the claimed design.

1 Claim, 8 Drawing Sheets
